Primary Examiner — Christian P. McLean*Assistant Examiner* — Jessica Lynn Devilbiss(74) *Attorney, Agent, or Firm* — Warner Norcross + Judd LLP(57) **CLAIM**

The ornamental design for a landing gear foot, as shown and described.

DESCRIPTION

FIG. 1 is a perspective view of the landing gear foot embodying the new design;

FIG. 2 is a right side view thereof, the left side view being a mirror image thereof;

FIG. 3 is a front view thereof;

FIG. 4 is a rear view thereof;

FIG. 5 is a top view thereof; and,

FIG. 6 is a bottom view thereof.

The figures show features in broken lines that do not form any part of the claimed design.
